UNITED STATES PATENT OFFICE.

CHARLES T. BRADY, OF DETROIT, MICHIGAN.

DESIGN FOR AN ILLUMINATED HAND MAGNIFYING GLASS.

Application filed June 9, 1927. Serial No. 22,371. Term of patent 14 years.

To all whom it may concern:

Be it known that I, CHARLES T. BRADY, a citizen of the United States, residing at Detroit, in the county of Wayne and State of Michigan, have invented a new, original, and ornamental Design for Illuminated Hand Magnifying Glass, of which the following is a specification, reference being had to the accompanying drawing, forming part thereof.

Figure 1 is a plan view of an illuminated hand magnifying glass;

Fig. 2 is a side elevation, and

Fig. 3 is a front end elevation thereof.

I claim:

The ornamental design for an illuminated hand magnifying glass, as shown.

CHARLES T. BRADY.
